ENTERTED APR 12 1870

United States Patent Office.

JAMES S. BRYANT, OF HARTFORD, CONNECTICUT.

Design No. 3,971, dated April 12, 1870.

DESIGN FOR A BLOTTING-PAD.

The Schedule referred to in these Letters Patent and making part of the same.

I, JAMES S. BRYANT, of Hartford, county of Hartford and State of Connecticut, have invented and produced a new and original Design for a Letter-copying-Book Blotter, of which the following is a specification.

The nature of my design is fully represented in the accompanying drawing, to which reference is made.

The letter a indicates the body of a curved blotter to be used in copying letters into a copying-book.

The letter b indicates the handle.

On the opposite or lower side of the curved body a are fastened thicknesses of blotting-paper, as many or as few as desired.

I claim as my invention—

The design for a letter-copying-book blotter, as set forth and shown.

JAMES S. BRYANT.
